UNITED STATES PATENT OFFICE.

WALTER F. RITTMAN, OF PITTSBURGH, PENNSYLVANIA.

APPARATUS FOR TREATMENT OF HYDROCARBONS.

1,352,917.

Specification of Letters Patent. Patented Sept. 14, 1920.

Application filed November 7, 1917. Serial No. 200,731.

To all whom it may concern:

Be it known that I, WALTER F. RITTMAN, residing at Pittsburgh, in the county of Allegheny and State of Pennsylvania, a citizen of the United States, have invented or discovered certain new and useful Improvements in Apparatus for Treatment of Hydrocarbons, of which improvement the following is a specification.

10 In an application filed Feb. 5th, 1917, Serial Number 146,720, is described and claimed a method of treating hydrocarbons having a high boiling point in such manner as to produce hydrocarbons of a lower boiling point, such method consisting substantially in subjecting the oil, while in a liquid state, to such a temperature as will, at least, initiate the cracking of some of the hydrocarbons and then vaporizing such partially 15 cracked hydrocarbons and subjecting the vapors to conditions of time, temperature and pressure dependent upon the end product desired.

The invention described herein relates to 20 certain improvements in apparatus for carrying out the above described method and consists, generally stated, in the provision of a retort or receptacle into which the liquid is fed and wherein it is subjected to 25 heat, the temperature of which will be dependent upon the character of the oil and the extent of cracking desired in this retort or receptacle, and of a retort into which the partially cracked hydrocarbons and any 30 vapors formed in the first retort are fed for their instantaneous vaporization of the liquid portions and subsequent to such vaporization subjected to conditions of temperature and pressure, the duration of which 35 will depend upon the character of the end products desired.

While not in all cases necessary, it will be generally preferred to so arrange the two retorts in which the hydrocarbons are 40 treated, that the latter will pass downwardly from one to the other and also to so arrange the retorts that all may be raised to the required temperature by heat from one or a common source. The invention is herein- 45 after more fully described and claimed.

In the accompanying drawing forming a part of this specification, Figure 1 is a sectional elevation of the upper portion of a furnace and retorts arranged therein; Fig. 2 is a sectional view of the upper portion of the main retort with the auxiliary re-

tort supported thereon; Fig. 3 is a sectional elevation of the upper portion of a main or vapor cracking retort, having the liquid cracking retort partially projecting into the upper end of the main retort; Figs. 4, 5 and 6 are views similar to Fig. 3 and illustrating means for transferring hydrocarbons from the liquid cracking or auxiliary retort into the main or vapor cracking retort; Fig. 7 is a sectional elevation showing the upper portion of the main retort and having the liquid cracking retort arranged in its upper end and rotatably supported therein, and also showing a means for detaching any carbon which may be formed and adhere to the sides of the liquid cracking retort; Fig. 8 is a view similar to Fig. 7 illustrating a modification thereof, as regards the manner of introducing the liquid into the liquid cracking retort; Fig. 9 is a transverse sectional view on the line IX-IX, Fig. 7.

In the practice of the invention, the main or vapor-cracking retort 1 is arranged, as is customary, in a suitable furnace 2, the upper and lower ends thereof preferably projecting beyond the top and bottom of the furnace so as to permit of ready access thereto. The liquid cracking retort 3 is so arranged that the movement of the hydrocarbons under treatment will be substantially vertical from one zone or phase of treatment to the next, until discharged from the lower end of the main retort. In Fig. 1 the cracking retort 3 is arranged in the upper portion of the vapor cracking retort 1 so as to receive heat from the furnace, which heat will be transmitted through the walls of the retort 1. It will be generally preferred to surround the portion of the retort 1 projecting above the furnace by non-conducting walls 3^a so as to prevent the loss of heat by radiation.

In treating hydrocarbons, the oil is fed by a pipe 4 into the retort 3, the pipe extending down a sufficient distance to discharge the oil near the bottom of the retort and beneath the surface of the oil contained therein. Communication is established between the retort 3 and the vapor cracking or main retort 1 by means of a tube 5 extending up into the auxiliary retort 3 a sufficient distance to maintain a desired amount of oil therein. In some cases, it may be preferred to discharge the liquid oil as such, but heated to or close to a vaporizing temperature, into the retort 1 and in such cases the rate

of flow into the retort 3 is so regulated as to maintain the desired flow through the top of the feed tube 5 into the retort 1.

In order to insure the vaporization of the oil as it enters the retort 1, it is caused to impact against a highly heated metal surface which may be either a metal disk, as 6, arranged immediately below the outlet of the tube 5, or as shown in Fig. 1, or the outlet tube 10 may be so arranged as to discharge against the walls of the retort 1. In some cases it may be desired to maintain a higher pressure in the retort 3 than in the vapor cracking retort, in which case provision will 15 be made for retarding the flow of the liquid from the retort 3 by contracting the inlet or discharge opening of the outlet tube 5 or by means of a valve having an operating handle extending through the top of the retort 3, as 20 shown in Fig. 6.

If desired, the retort 3 may be supported upon the stirring rod 8 as shown in Figs. 7 and 8, in which case the retort 3 will be arranged entirely within the retort 1 and will 25 be capable of being rotated with the stirring rod. This construction would permit of the employment of a scraper for removing any carbon which may be formed on the walls of the retort 3. As shown therein, 30 this scraper consists of a series of blades 9 secured to a suitable support, as the feed pipe 4 and projecting radially so as to contact with the outer walls of the retort. In this construction, the support for the wings 35 will be held stationary while the retort is rotated.

If desired, the oil to be treated may be fed up through the stirring rod into the retort 3 and the oil may be discharged from the 40 retort through a series of perforations in the upper portion of the retort, as shown in Figs. 7 and 8.

It is characteristic of the construction shown and described herein that by regulating the flow of material into the auxiliary retort 3, entire vaporization in addition to the cracking may be effected as shown in Fig. 1, the level of the oil being kept below the upper end of the tube 5, or by maintaining a level of oil above the upper end of this tube, oil will be fed into the main or cracking retort and vaporized immediately on its entrance thereto. Generally, such a temperature will be maintained in the auxiliary retort as to effect cracking of the oil in the liquid phase, provided other conditions required for cracking are maintained at the same time, and this cracking will be extended and completed in the main retort 1.

60 It is further characteristic of the apparatus described herein, that the cracking both in the liquid and the gaseous phase and also at the vaporization stage, whether effected in the auxiliary or in the main retort, is effected by heat from the common source, thus

carrying out the heat cycle forming the subject matter of an application filed February 5, 1917, Serial Number 146,725.

I claim herein as my invention:

1. In an apparatus for treating hydrocarbons, the combination of a furnace, a main retort arranged in a substantially vertical position in said furnace, an auxiliary retort arranged in such relation to the main retort as to receive heat therefrom, means for feeding oil into the auxiliary retort, means for maintaining a body of oil in said auxiliary retort and means for conducting fluid from the auxiliary retort into the main retort. 70

2. In an apparatus for treating hydrocarbons, the combination of a furnace, a main retort arranged in a substantially vertical position in said furnace, an auxiliary retort arranged in line vertically with the main retort and adapted to receive heat 75 therefrom, means for feeding oil into the auxiliary retort, means for maintaining a body of oil in said auxiliary retort and means for conducting fluid from the auxiliary retort into the main retort. 80

25 3. The combination of a furnace, a main retort arranged in a substantially vertical position in said furnace and having an outlet adjacent to its lower end, an auxiliary retort arranged in line vertically with the main retort, means for conducting fluid from the auxiliary retort, means for maintaining a body of oil in said auxiliary retort into the upper portion of the main retort and means 90 for feeding oil into the auxiliary retort. 95

4. In an apparatus for treating hydrocarbons, the combination of a furnace, a main retort arranged in a substantially vertical position in said furnace, an auxiliary retort arranged in such relation to the main retort 100 as to receive heat from the main retort, means for feeding oil into the auxiliary retort, means for maintaining a body of oil in said auxiliary retort, a connection from the auxiliary retort to the upper portion of the 105 main retort.

5. In an apparatus for treating hydrocarbons, the combination of a furnace, a main retort arranged in a substantially vertical position in the furnace, an auxiliary retort 110 arranged in such relation to the main retort as to receive heat from the main retort, means for feeding oil into the auxiliary retort, means for maintaining a body of oil in said auxiliary retort, a connection from the 115 auxiliary retort to the upper portion of the main portion of the main retort, and adapted to direct the fluid against the highly heated surface within the main retort. 120

6. In an apparatus for treating hydrocarbons, the combination of a furnace, a main retort arranged in a substantially vertical position in the furnace, an auxiliary retort 125 arranged above the main retort and provided with means to close the upper end of 130

the main retort, means for feeding oil into the auxiliary retort, means for maintaining a body of oil in said auxiliary retort and means for conducting fluid from the auxiliary retort into the main retort.

7. In an apparatus for treating hydrocarbons, the combination of a furnace, a main retort arranged in a substantially vertical position in the said furnace, an auxiliary retort arranged above the main retort and hav-

ing its lower end adapted to close the upper end of the main retort, means for feeding oil into the auxiliary retort, means for maintaining a body of oil in said auxiliary retort and means for conducting fluid from the auxiliary retort into the main retort.

In testimony whereof I have hereunto set my hand.

WALTER F. RITTMAN.
